APPARATUS FOR LAUNCHING LIFEBOATS

Richard Clarke Wilson, Miami, Fla.

Application March 5, 1935, Serial No. 9,486

7 Claims. (Cl. 9—22)

This invention relates to devices or apparatus for launching life boats from the decks of a vessel.

Heretofore it has been the practice to launch life boats by lowering them down the sides of a vessel by various mechanical and manual means, which practice has been unsatisfactory and hazardous, inasmuch as the boats are often smashed against the vessel by a heavy sea with resulting damage to life and boats. Furthermore, the complicated system of tackles, pulleys and cables necessary to operate these life boats have necessitated a relatively large life boat crew which has proved confusing and cumbersome in an emergency, and adds to the delay in launching the boats. Due to their size and complex operating mechanisms these devices have appropriated valuable ship space for stowage purposes, thereby curtailing the space allotted to state rooms and promenade decks of large liners. These devices have also proved objectionable and undesirable due to their overhanging cradles and lowering frames which hamper the vessel in docking or maneuvering alongside another vessel.

The principal object of my invention is to provide a boat supporting unit for supporting the boats in an inverted position on the upper deck of a ship, from which position they may be swung outboard into upright position at a point opposite one of the lower decks preparatory to launching.

Another object of my invention is to provide a boat supporting unit for supporting two boats side by side in an inverted position on the upper deck of a ship, from which position they are swung outboard into upright position at a point opposite one of the lower decks, and provided with means whereby the inner boat may be launched from the same point on the supporting unit as the outer boat.

Another object is to provide an automatic motor or manually controlled life boat launching apparatus which will launch the boats safely when the vessel is at list of approximately fifteen degrees.

Another object is to provide a launching apparatus which will launch life boats from a lower level during average weather and from a higher level during rough weather.

Another object is to provide a launching apparatus which will require a comparatively small crew of three men to launch and restow each unit of two boats, thus simplifying and speeding up launching operations with more efficiency thereby permitting more life boat crew drilling during a voyage, which, at the same time, will be instru-

mental in familiarizing the passengers therewith which will prove advantageous in an emergency.

Another object is to provide a launching apparatus whereby the boat crews can report at boat loading stations below the boat stowage spaces, while the boats are being lowered thereto by remote control, thereby eliminating crew handling in breaking out of the boats with its resulting confusion and delay.

A further object is to provide a launching apparatus wherein the actual launching and sending away of the boats is controlled by an officer stationed nearby at the ship's rail, thereby preventing any danger of conflicting or misunderstanding of orders.

A further object is to provide a launching apparatus employing linked chain cables, thereby eliminating objectionable rope or wire cables which have a tendency to kink or become otherwise misshapen and jam the apparatus.

A further object is to provide a novel means for automatically locking the boat carrying apparatus in stowed or inoperative position.

Other and more specific objects and advantages will be apparent as the specification is considered in connection with the accompanying drawings illustrating an embodiment of the invention, in which:

Figure 1 is a view of the side of the ship showing a front elevation of the launching apparatus;

Figure 2 is a top plan view, partly in section, of the boats in stowed position;

Figure 3 is an enlarged side elevation of the carrying crane showing the automatic locking and driving means therefor;

Figure 4 is an enlarged side view of the locking means;

Figure 5 is a side elevation of the carrying crane with the boats in loading position; and

Figure 6 is a plan view of one of the carrying crane arms with the boats in position preparatory to lowering.

Referring more particularly to the drawings, in which similar reference characters indicate corresponding parts throughout the several views, numeral 1 denotes two motor powered life boats A and B respectively. The boats 1 are adapted to rest in inverted position (as in Figure 1) upon a pair of relatively wide metal supporting standards or skids 2 of a substantially L-shaped metal carrying frame 3. The supporting standards 2 of the carrying frame 3 have two integrally formed vertical relatively wide metal rail arms 4, which arms are pivoted by means of bolts or the like 5 on their lower ends, to lugs or suitable brackets 55

6 on a ship's deck 1, adjacent the outboard edge thereof. The supporting standards 2 are provided with suitable stop blocks or lugs 8, at the outer ends thereof, for retaining the boats in stowed position. Recesses, or the like, 9 are provided in the outboard edge of a deck 10 into which the vertical rail arms 4 fit when the carrying frame is in stowed or inoperative position, thereby presenting a flushed side to the vessel. Grips or 10 stop lashings 11 of suitable construction, preferably four in number, are fastened at one end to gripe hooks 11', positioned in the deck 7, and extend over the inverted bottoms of the boats 1 and are hooked by means of gripe hooks 36 under pins 33, to be presently described, thereby lashing the boats and carrying crane to the deck 10.

A remote controlled electric motor 13 is suitably positioned, for the purpose of illustration, on the side of a deck house 14. A worm and gear 20 mechanism 15, carried by a rotating shaft 16 and actuated by the motor 13, is suitably suspended from the underside of the upper deck 10. A main drive shaft 17 extending through the worm and gear housing 15 is suitably journaled in bearings or the like 18, positioned in the cross beams 19 of the upper deck 10.

The drive shaft 17 carries a toothed gear, or chain wildcat 20 at both ends thereof, which gears engage and operate two main launching chains 30 or falls 21. The idle ends of the chains are adapted to be received and stowed in two vertical pipes 22, positioned below the gears 20 and extending down into the hold of the vessel. If desired, suitable idlers or rollers, not shown, may be suitably positioned adjacent the gears, thereby serving to prevent the launching chains from slipping from the gears.

Two substantially U-shaped floating levers or bell cranks 24, positioned in the recesses 9 of the upper deck 10, above and to the rear of the gears 20, are pivoted at their inner ends 25 by means of axles 26 suitably journaled in brackets or ears 27. A relatively short spring 27', connected to the inner ends of the bell cranks, and to a suitable bracket in the deck 10, serves to return the crank levers to normal position. The bell cranks 24 carry two rollers or fairleaders 28 at the outer upper ends 29 thereof, which rollers are mounted on axles 30, extended as at 31, suitably journaled in the bell crank 24. The inner upper ends 31 of the fulcrumed ends 25 of the crank arms are connected to and actuate two rods or links 32, which in turn are connected to and slidably operate two pins 33, suitably mounted in apertures 34 of brackets 35, positioned on the inner edge of the deck 10. The hooked free ends 36 of the grips or stop lashings 11 hook or fit under the outer ends 38 of the pins 33, when the latter pins are in closed position, that is, when the boats are in stowed or inverted position. The main launching chains or falls 21, engaging the gears or wildcats 20, pass over the rollers or fairleaders 28 and extend over two sheaves 34a, suitably supported in the supporting standards 2, and are fastened by means of suitable releasing hooks, not shown, to the boats 1. The supporting standards 2 are provided with beveled lugs or flanges 39 which engage the extended axle ends 37 of the rollers or fairleaders 28, thereby depressing the rollers and causing the extended axles 37 thereof to engage the lugs 39 and locking the boats in their stowed or inoperative position.

In order to automatically launch or lower the 75 boats, the motor is switched on by remote con-

trol, from the pilot house or other suitable station. By rotation of the successive shafts 16 and 17, the gears or wildcats 20 are rotated thereby causing the linked launching chains 21 to be tightened up on the gears which causes the depressing or lowering of the rollers 28 and the disengaging of their extended axles 37 from the lugs or flanges 39 of the supporting standards, thereby unlocking or freeing the standards. At the same time the depressing of the rollers 28 automatically withdraws the pins 33 from the brackets 35 and causes the hooks 36 of the grips 11 to be released, thereby unlashing the boats and supporting standards from the upper deck 10. The continued tightening of the launching chains causes the carrying crane and boats to be swung upwardly in an arc until the chains are relatively perpendicular to the deck, at which point a suitable switch 42, positioned on the deck rail 43 is thrown to reverse the motor. If desired, a suitable switch, not shown, may be suitably positioned in the path of the chain falls, whereby the motor will be automatically reversed. The reversal of the motor causes the wildcats 20 to reverse, whereby the chains are payed out or slackened away, thereby lowering the boats outwardly and downwardly to their lower deck lever 7a loading stations, as shown in Figure 1. When, in lowering the boats, the vertical rail arms 4 reach the ship's side, a switch lever 39', suitably positioned in the ship's side, 30 is contacted thereby automatically shutting off the motor. Suitable pivoted hooks or the like 41 positioned on the deck, may be clamped against the carrying crane to firmly lash the latter to the side of the vessel.

The relatively wide metal supporting standards 2 and rail arms 4 are provided with a plurality of rungs or grill members 56a, to provide a walkway for the crew who aid in loading the passengers into the respective life boats. When life 40 boat A is ready for launching, an operator, preferably stationed on boat-loading deck 7a, throws the switch lever 42, thereby starting the motor in reverse and lowering A boat down to the water. The launching chains 21 are released from their respective boat launching latches 44 of usual construction by a member of the crew stationed at each end of the boat.

A sliding track or skid groove 45 is built into the supporting standards 2 by means of angle 50 metal frames or the like 46, upon which tracks or skids, guide arms 47 of boat supporting carriages 48 are adapted to slide. Boat B is removably connected to the sliding supporting carriages 48 by threaded jack screws 49 which are threadedly received therethrough. Boat B may be loaded at the same time as boat A, whereupon the latter boat being lowered, boat B is lowered approximately three or four inches at each end by rotating the jack screws 49 until its gunwales clear or free the retaining lugs or stop blocks 8, at which time the boat is ready to be moved outboard. The disengaged launching chains 21 from boat A are hauled up and fastened to suitable safety pins or hooks 50 on boat B, whereupon the chains are tightened by the motor, and the boat is immediately pulled outboard to the position occupied by boat A. When loaded, the boat is lowered to the water and released from the chains 21 by suitable 60 safety levers of usual construction, not shown.

Should the lifeboats return to the vessel after effecting a rescue or the like, boat B is preferably the first to be hoisted from the water to the supporting standards 2 by connecting the launching 75

chains, as described, and starting the motor; then returning the boat inboard by reversing the heretofore described operation. The jack screws 49 are tightened up and the boat lifted approximately 5 two or three inches to be firmly positioned by the retaining lugs 8. Boat A may then be hauled up by the launching chains until it reaches the supporting standards 2. The continued hauling or 10 tightening of the chains causes the whole carrying crane and boats to be lifted up until the chains 21 are relatively perpendicular to the deck 10, at which point the motor is reversed by throwing the reversing switch 42 and the crane lowered. In reversing the carrying crane to the deck 10, 15 the lugs 39 of the supporting standards will engage and depress the rollers 28, as described, thereby automatically locking the carrying crane and boats in stowed position. The gripe or stop lashings 11 may then be readily positioned over 20 the boats by members of the crew and the hooked ends 36 thereof fitted under the extended ends of the pins 33.

During stormy weather it is often a hazardous 25 undertaking to launch life boats at the normal lower deck level, as there is the ever present danger of the waves striking the boats. When it is desired to launch at a higher deck level the crane will be lowered until the rail arms 4 are level with deck 7, at which position the motor 30 is stopped and an extra pair of heavy guys 52 stored in boat B for the purposes of illustration, are connected at one end by suitable hooks 52a to the rungs 56a, and at their other end to suitably positioned clasp hooks 53 on deck 10, thereby firmly retaining the carrying crane in an elevated position. Boat A may then be lowered on the launching chains until it is freely suspended beneath boat B at the end of the rail arms, where it may readily be loaded and lowered away. After 40 boat A has left the vessel the launching cables may be hoisted and the ends hooked into the launching pins 59 of boat B. The boat is then hoisted a few inches until its weight is on the launching chains, thereby permitting the disengaging of the jack screws 49. The slackening of 45 the launching chains lowers the boat to its loading position beneath the ends of the rail arms, from where it is lowered when ready.

In order to launch the boats when the vessel 50 is at a list of approximately fifteen degrees, the supporting arms 2 of the carrying crane are provided with relatively short metal folding arms 54, pivotally connected as at 55, adjacent the ends 55 of the supporting arms. When the boat is at a list and the life boats are in stowed position, the metal folding arms 54 are pulled downwardly into upright position. The outer ends of the arms are slotted, as at 55a, whereby the launching chains 60 are slackened to permit them to be inserted through the slotted ends 55a of the arms. Therefore, when the carrying crane is in launching position, the chains passing over the upright arms 54 will lower the boats vertically, thereby overcoming the list of the vessel.

The outer end of the rotating shaft 16 of the motor installation is provided with a suitable gear wheel 56 which is adapted to be manually controlled by a suitable chain fall 57, whereby the drive shaft 17 and chain wildcats 20 may be driven by hand in the event the motor installation becomes damaged or out of order in an emergency.

By reason of the herein described launching 75 apparatus both life boats are adapted to be low-

ered from their stowed position on the upper deck to their loading deck positions 7a in the relatively short period of approximately thirty seconds. It is to be understood that, while I have described as a preferred embodiment of my apparatus a double life boat launching means, it is also adaptable for use with a single boat, or more than two, should this be desirable.

While I have in the present instance shown and described preferred embodiments of my invention 10 which will give in practice satisfactory and reliable results, it is to be understood that the same are susceptible of modification or rearrangement in various particulars without departing from the spirit or scope of the invention or sacrificing any 15 of its advantages.

Having thus described my invention,

What I claim is:

1. A life boat launching apparatus, comprising substantially L-shaped pivoted supporting davits 20 adapted to have life boats stowed thereon in inverted position, power means for moving said frames outboard to place said boats in normal loading position, flexible cables connected to said power means and one of said boats for actuating 25 said davits, pivoted means for locking said davits in and disengaging said davits from their stowed position, said means being adapted to be actuated by said cables.

2. A life boat launching apparatus, comprising 30 substantially L-shaped pivoted supporting davits adapted to have life boats stowed thereon in inverted position, power means for moving said davits outboard to place said boats in upright 35 position, flexible cables connected to said power means and one of said boats for raising and lowering said frames and boats, flexible means for lashing said boats in stowed position, means for automatically locking said davits in and disengaging said davits and flexible locking means 40 from their stowed position when said power means is operated.

3. A life boat launching apparatus, comprising a pair of substantially L-shaped pivoted supporting members adapted to have life boats 45 stowed thereon in inverted position, power means for vertically rotating said members to place the life boats in normal position beyond the side of the vessel for loading, said means comprising cable drums mounted on said power means, flexible 50 cables operatively connected to said drums and extending to said supporting members, said cables adapted to be disengageably connected to said boats, means actuated by said flexible cables 55 for locking and releasing said supporting members to lower members to launching position.

4. A life boat launching apparatus, comprising a pair of substantially L-shaped pivoted supporting members adapted to have life boats stowed thereon in inverted position, power means for 60 vertically rotating said members to a position against the side of the vessel to place the life boats in normal loading position beyond the side of the vessel, said means comprising two cable drums mounted on said power means, flexible 65 cables operatively connected to said drums and extending to said members, said cables adapted to be disengageably connected to said boats, pivoted means adjacent said drums, said flexible cables being adapted to actuate said pivoted 70 means for locking and releasing said supporting members to lower or stow said members.

5. A life boat launching apparatus, comprising 75 a pair of substantially L-shaped pivoted frame

supporting members adapted to have life boats stowed thereon in inverted position, geared power means for vertically rotating and lowering said members to a position against the side of the vessel to place the life boats in normal loading position beyond the side of the vessel, said means comprising two cable drums mounted on said power means, flexible cables operatively connected to said drums and extending to said members, said cables adapted to be disengageably connected to said boats, flexible lashing cables for retaining the life boats in stowed position, pivoted locking members adjacent said drums, means on said supporting members adapted to engage said pivoted members, said flexible cables being adapted to actuate said pivoted locking members for releasing said flexible lashing cables and said supporting members when launching said boats.

20 6. In a life boat launching apparatus, the combination with a pair of substantially L-shaped supporting members hinged to swing outwardly, means for operating said members comprising a main shaft, a pair of cable drums mounted thereon, gear mechanism on said main shaft, a main shaft, flexible controlling cables operatively connected with said cable drums and arranged to pass through said supporting members, said cables adapted to be detachably connected to a life boat, pivoted spring means adjacent said drums for locking and disengaging said supporting members, said means being adapted to be actuated by said controlling cables.

motor having driving connections with said geared main shaft, cables operatively connected with said cable drums and extending to said supporting members, said cables adapted to be detachably connected to a life boat, means adjacent said cable drums for locking and disengaging said members, said means being adapted to be actuated by said cables.

7. In a life boat launching apparatus, the combination with a pair of L-shaped frame supporting members hinged to swing outwardly, means for operating said members, comprising a main shaft, a pair of cable drums mounted thereon, gear mechanism on said main shaft, a motor having driving connections with said geared main shaft, flexible controlling cables operatively connected with said cable drums and arranged to pass through said supporting members, said cables adapted to be detachably connected to a life boat, pivoted spring means adjacent said drums for locking and disengaging said supporting members, said means being adapted to be actuated by said cables.

RICHARD CLARKE WILSON. 25
